CLAIM

The ornamental design for an insole, as shown and described.

DESCRIPTION

FIG. 1 is a top plan view of an insole showing our new design;

FIG. 2 is a bottom plan view thereof;

FIG. 3 is a top, rear perspective view thereof;

FIG. 4 is a rear elevation view thereof;

FIG. 5 is a front elevation view thereof;

FIG. 6 is a right side elevation view thereof; and,

FIG. 7 is a left side elevation view thereof.

The hexagon pattern is shown in broken lines and forms no part of the claimed design.

1 Claim, 5 Drawing Sheets
